UNITED STATES PATENT OFFICE.

FRANK M. HUNT, OF ROUND OAK, GEORGIA.

FLY-FAN.

SPECIFICATION forming part of Letters Patent No. 278,140, dated May 22, 1883.

Application filed April 10, 1883. (No model.)

To all whom it may concern:

Be it known that I, FRANK M. HUNT, a citizen of the United States, residing at Round Oak, in the county of Jones and State of Georgia, have invented certain new and useful Improvements in Fly-Fans, of which the following is a specification, reference being had thereto in the accompanying drawings.

This invention relates to certain improvements in fly-fans; and it has for its objects to provide certain improved means for imparting an oscillating motion to the fan-arms which carry the fan-sheets, as more fully hereinafter specified. These objects I attain by the means illustrated in the accompanying drawings, in which—

Figure 1 represents a perspective view of my improved device, and Fig. 2 a transverse vertical sectional view of the same.

20 The letter A indicates an upright box or casing, containing a train of cog-gearing, B, actuated by a spring, C, which rotates the driving-shaft D, the latter projecting and being squared at the end E, so that it may be wound by means of a suitable key.

The letter F indicates the usual ratchet and pawl to arrest backward movement of the shaft and permit winding.

The shaft of the upper cog-wheel of the train (indicated by the letter G) projects at each side, and to the ends are rigidly secured the plates H, which are provided with curved fingers I, as indicated. These plates are placed in opposite directions on the opposite sides of the

apparatus, for the purpose hereinafter explained.

The letter I indicates a vertical shaft, mounted in suitable bearings in a frame, K, at the top of the apparatus. The said shaft projects above the top of the frame, and is provided with horizontal arms L, which carry the fan-sheets M. To the said vertical shaft is secured a horizontal wheel, having radial arms N, as indicated.

The operation of my invention is as follows: 45 The train of gearing, being put in motion by means of the spring, will rotate the shaft G so as to carry the plates in the direction of the arrows. The fingers on the said plates will alternately engage the arms N, giving an oscillating movement to the fan.

Having thus described my invention, what I claim, and desire to secure by Letters Patent, is—

In a fly-fan, the combination of the actuating-gearing located in a suitable casing, the plates carrying fingers, mounted on the upper shaft of said gearing, the vertical shaft carrying the fan, and having mounted upon it a wheel having radial arms, and actuated by 55 the fingers of the plates to give an oscillating motion to the fan, substantially as specified.

In testimony whereof I affix my signature in presence of two witnesses.

FRANK M. HUNT.
